REFRIGERATING APPARATUS

Regis D. Heitchue, Springfield, Mass., assignor
to Westinghouse Electric Corporation, East
Pittsburgh, Pa., a corporation of Pennsylvania

Application September 6, 1943, Serial No. 501,384

8 Claims. (CL 62—3)

1

My invention relates to refrigerating apparatus, and more particularly to a motor-compressor unit therefor, and it has for an object to provide improved apparatus of the character set forth.

In selecting a motor to drive the compressor of a refrigerating system, consideration must be given to the torque required to drive the compressor during what is commonly termed the pull-down period. That is, after the refrigerating system has been shut down for some time, the suction pressure is much higher than during normal operation. The torque required to drive the compressor while the suction pressure is above normal, which is the "pull-down" period, is usually considerably in excess of the normal torque required, particularly when the refrigerating system normally operates at a relatively low suction pressure or temperature. This is due to the fact that at higher suction pressure, the density of the gas is higher so that more power is required to compress the greater mass of the refrigerant gas. In one compressor, for example, which normally operates at a suction pressure corresponding to 5° F., the motor input is increased more than 50% when the suction temperature is 50° F.

It is an object of my invention to eliminate the necessity for such a high torque during the pull-down period so that a smaller motor may be used and the cost of the apparatus thereby reduced.

In accordance with my invention, I provide one or more cylinders of the compressor with an unloader mechanism and I also provide a control for unloading one or more but not all of the cylinders of the compressor in response to high suction pressure, so that during the pull-down period, the load on the motor is held down to a value within the capacity of the motor, while another cylinder or cylinders are operated to reduce the suction pressure. When the suction pressure has been reduced to substantially its normal value, then the remaining cylinders may be loaded.

Compressors for refrigerating systems are frequently provided with unloader mechanisms to reduce the capacity or output of the compressor in accordance with varying load requirements. In connection with such compressors, it is a further object of my invention to accomplish the aforesaid object of reducing the size of the motor with a minimum of additional apparatus. This I accomplish by utilizing the same cylinder unloader mechanisms for both varying the capacity or output of the compressor in accordance with variations in load and also for unloading one or more cylinders to reduce the load during the pull-down period.

2

These and other objects are effected by my invention as will be apparent from the following description and claims taken in accordance with the accompanying drawings, forming a part of this application, in which:

Fig. 1 is a diagrammatic view of one embodiment of my invention utilizing a pull-down control and temperature control for operating the unloader mechanisms;

Fig. 2 is a sectional view of one of the unloader mechanisms shown in Fig. 1;

Fig. 3 is a sectional view of the solenoid-operated pilot valve employed in Fig. 1; and,

Fig. 4 is a diagrammatic view of a second embodiment of my invention utilizing a pull-down control and a suction pressure control for operating the unloader mechanism.

Referring specifically to Figs. 1, 2 and 3 of the drawings for a detailed description of the first embodiment of my invention, I show a six-cylinder compressor 10 driven by an electric motor 11. In accordance with the present invention, the motor 11 need only be of sufficient capacity to drive the compressor when the suction pressure is down substantially to its normal value. It need not be of sufficient capacity to drive the compressor fully loaded during the pull-down period, when the higher density of the suction gas imposes greater load per cylinder. The compressor and motor are preferably enclosed in a fluidtight casing 12. Compressed refrigerant is conveyed through a conduit 13 to a condenser diagrammatically shown at 14, from which condensed refrigerant is conveyed through a conduit 15 and an expansion valve 16 to an evaporator 17. The evaporator 17 is disposed in an enclosure wherein the air is to be cooled or conditioned. The vaporized refrigerant is conveyed from the evaporator through a suction conduit 18 to the motor-compressor unit. The expansion valve 16 may be of any suitable type, for example, it may be a thermostatic expansion valve having a thermostatic bulb 19 subjected to the temperature of the suction conduit 18 and regulating the flow of refrigerant to the evaporator to maintain a constant degree of superheat of the vaporized refrigerant leaving the evaporator.

The six cylinders are divided into three pairs of cylinders, each pair being provided with a common cylinder head 21 and a pair of unloader mechanisms 22. Referring to Fig. 2, the cylinder head 21 is formed with an inlet chamber 23 and a discharge chamber 24. The inlet chambers 23 of the several cylinders communicate with the suction conduit 18 through the motor-contain-

ing portion of the sealed casing 12 and suitable passage (not shown) provided in the casing. The discharge chambers 24 communicate with the discharge conduit 13 through other suitable passages (not shown) formed in the casing 12. A valve cage 25 is clamped between each cylinder and the cylinder head associated therewith, and contains the suction and discharge valves for controlling flow of refrigerant gas between the cylinder and the suction and discharge chambers 23 and 24, respectively. The suction valves are pressure operated, suction valve 26 in Fig. 2 being of the reed type. By holding the reeds of the valve 26 down, the cylinder is unloaded, since refrigerant gas may return to the suction chamber 23 upon upward movement of the piston in the cylinder.

The unloader mechanism 22 for each cylinder, shown in Fig. 2, is operated in the unloading direction by the discharge pressure of the compressor. The unloading mechanism 22 comprises a bar 27 which may be, as shown, attached to a rod 28 that extends through the cylinder head 21. The bar 27 carries fingers 29 adapted to engage the several reeds of the valve 26. A bellows 30 contained in a sealed casing 31 actuates the rod 28 and may be directly connected to it.

The bellows 30 for the first, second and third sets of cylinders are controlled by solenoid-operated pilot valves 32, 33 and 34, respectively, constructed as shown in Fig. 3. Each pilot valve is connected to a conduit 35 which communicates with the two bellows 30 of the associated pair of cylinders, a conduit 36 which communicates with the compressor discharge through the conduit 13, and a conduit 37 which communicates with the crankcase of the compressor, which is at suction pressure by reason of communication with the suction passages within the casing 12 of the motor-compressor unit. When the solenoid is deenergized, as shown in Fig. 3, the pilot valve places the conduits 35 and 36 in communication, thereby applying compressor discharge pressure to the unloaders and unloading the associated pair of cylinders by depressing the fingers 29 to hold the valve reeds open. When the solenoid is energized, the pilot valve places conduits 35 and 37 in communication, thereby applying suction pressure to the unloaders, so that the bellows 30 expands and loads the associated pair of cylinders by retracting the fingers 29.

Referring again to Fig. 1, I show an unloader control system which maintains the compressor 10 completely unloaded during starting after an inactive period, partially unloads the compressor during pull-down, and serves to control the temperature of the media to be refrigerated by partially unloading or fully loading the compressor.

In order to accomplish these functions, I provide a control 38 having an element 39 responsive to the temperature of the media to be refrigerated, that is, the air in the enclosure cooled by the evaporator 17, and having fixed contacts 40, 41 and 42 connected to the solenoid-operated pilot valves 32, 33 and 34, respectively, and a movable contact 43 which is capable of engaging one, two or all three of said fixed contacts, or of being completely disengaged therefrom. I also provide a starting relay 44 and an electrically-operated time delay relay 45. I furthermore provide a pull-down control device 46 which is responsive to suction pressure by communication of a bellows 47 with the interior or suction pressure zone of the sealed casing 12 through a conduit 48. The bellows operates a pivoted lever 49

5 to which is attached a flexible member 50 having two movable contacts 51 and 53 which are adapted to successively engage two fixed contacts 52 and 54, respectively. Two stops 55 are provided to limit the travel of the lever 48.

10 The contacts 54 and 52 are connected to the solenoid-operated pilot valves 33 and 34, respectively, in series with the contacts 41 and 42, respectively. Accordingly, each of these valves is deenergized to unload the associated cylinders whenever the circuit therethrough is opened at either of its contacts.

15 The electrical connections are clearly shown in Fig. 1 and further description is not thought necessary.

Operation

Assume the system has been shut down for some time by the opening of the line switch 57. The control system will be in the position shown in Fig. 1 and the control 38 will be in such position that the movable contact 43 will be in engagement with all three of the fixed contacts 40, 41 and 42. This is because the temperature in the enclosure to be cooled has increased and the temperature-responsive element 39 has moved the movable contact 43 into the position shown. The pull-down control 46 will be in the position shown in Fig. 1 with all contacts open because the suction pressure will be relatively high. When the line switch 57 is closed to connect the electrical control circuit to line L₁, L₂, the starting relay 44 is closed and motor 11 is energized. However, as the contacts 53 and 59 are open, all the cylinders are unloaded at this time so that the motor reaches its normal operating speed in a few seconds. The time delay relay 45 is also energized and after a few seconds a movable contact 56 associated therewith bridges contacts 59, thereby energizing the first pilot valve 32 and loading its associated pair of cylinders. Due to the high suction pressure and density of the gas to be compressed, the load on a loaded cylinder is now greater than normal. However, since only one-third of the cylinders are loaded, the total load on the motor is not greater than normal.

50 Operation continues with one pair of cylinders loaded, and assuming that the control 38 still calls for refrigeration, the suction pressure in the refrigerating system decreases until it reaches a value of, for example, 60 pounds per square inch gauge, when dichlorodifluoromethane is the refrigerant used. The bellows 47 of the control 46 then contracts and contacts 53 and 54 are closed. Pilot valve 33 is thereby energized and the second 55 pair of cylinders is loaded. The density of the refrigerant gas is now sufficiently low that four cylinders may be operated without overloading the motor. As the suction pressure decreases to a lower value, for example, 50 pounds per square 60 inch gauge, the bellows 47 contracts still further and contacts 51 and 52 are closed, thereby energizing pilot valve 34 and loading the third pair of cylinders. Thus the compressor is completely 65 loaded, the density of the refrigerant gas being sufficiently low.

As the temperature in the enclosure decreases, the temperature-responsive element moves the movable contact 43 of control 38 first out of engagement with contact 42, thus deenergizing the pilot valve 34 and unloading its associated pair of cylinders. This may occur, for example, when the temperature drops below 80° F. A further drop in temperature to below, for example, 79° F. moves contact 43 out of engagement with contact 41, thus deenergizing pilot valve 33 and un-

loading its associated pair of cylinders. When the demand for refrigeration is completely satisfied, for example, when the temperature drops to below 78° F., contact 43 is moved out of engagement with contact 40, thus deenergizing the motor 11 and shutting down the system. Upon increase in temperature, the contact 43 moves downwardly to start the compressor or load additional cylinders, as will be readily understood.

If there is again a demand for refrigeration before the suction pressure rises above 50 pounds per square inch gauge, the control 38 loads either one, two or three pairs of cylinders, depending on the demand, and the suction pressure control 46 does not function to effect unloading. If, however, refrigeration has not been required for some time, the suction pressure may rise sufficiently to open contacts 53 and 54 or to open both contacts 53, 54 and 51, 52, thereby unloading one or two pairs of cylinders depending on which contacts are opened, until the suction pressure reaches its normal operating value.

Since the contacts of the control 38 are in series with the respective contacts of the control 46, the contacts of either control are adapted to effect unloading of the associated cylinders, regardless of the action of the other control.

Figure 4

Fig. 4 shows exactly the same unloader and control system as shown in Fig. 1, for use with the same refrigerating system, except that the control 38' is provided with a bellows 56 which is responsive to the suction pressure in the refrigerating system, instead of the temperature-responsive element 39 of the first embodiment. Accordingly, the operation of the motor-compressor unit is controlled to maintain the suction pressure substantially constant. The control 38' may be so arranged that the movable contact 43 engages the fixed contacts 40, 41 and 42 as the suction pressure increases to 33, 35 and 37 pounds per square inch, respectively.

The operation is generally the same as that of the first embodiment. The pull-down control 46 operates in exactly the same way during the pull-down period to limit the load on the motor. After the pull-down, the control 38' controls the operation of the compressor to maintain the suction pressure substantially constant. As the suction pressure decreases to 37 pounds and to 35 pounds per square inch, respectively, the movable contact disengages the contacts 42 and 41 to unload first one and then a second pair of cylinders. Upon a further decrease to 33 pounds per square inch the contact 43 disengages the contact 40 to shut down the compressor unit. Conversely, upon increase in pressure, the contact 43 engages to contact 40 to start operation and the contacts 41 and 42 to load additional pairs of cylinders.

Assume that the refrigerating system has been shut down for a time sufficient to permit the suction pressure to increase to 60 pounds per square inch and that the load when operating is relatively light. Upon closing the line switch 51, all cylinders are unloaded until the motor-compressor unit comes up to speed, after which the pilot valve 32 will load two of the cylinders. As the suction pressure drops to 60 and 50 pounds per square inch, respectively, additional pairs of cylinders will be loaded. The motor-compressor unit will then continue to operate until the suction pressure drops down to 37 pounds per square inch, whereupon the control 38' will again unload one pair of cylinders and as the suction pressure

drops to 35 pounds per square inch, another pair of cylinders will be unloaded.

It may be noted that in this embodiment the controls 38' and 46 will never, assuming the apparatus to be in proper working condition, effect unloading at the same time. The control 46 will effect unloading only above 50 pounds per square inch and the control 38' will effect unloading only below 37 pounds per square inch.

It is, therefore, clear that I have provided an improved control system for unloaders in a refrigerating system which completely unloads the compressor for starting, partially unloads the compressor during pull-down, and controls the temperature or suction pressure of the system during normal operation.

From the above description, it will be seen that, by combining the two controls, I am able to utilize the same set of unloader mechanisms both to reduce the load during pull-down, thereby reducing the size and cost of the motor that is required, and also to provide partial load operation, which reduces cycling and provides more satisfactory operation.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

What I claim is:

1. In a refrigerating system having a high-pressure side including a refrigerant condenser and a low-pressure side including a refrigerant evaporator for cooling a media, the combination of a refrigerant compressor for withdrawing refrigerant from the low-pressure side of the system and compressing it into the high-pressure side of the system, a prime mover for driving the compressor, said refrigerating system having active and inactive periods and having a high pressure prevailing in the low-pressure side of the system after an inactive period of such duration that the evaporator approaches ambient temperature, means for partially unloading the compressor during the first part of the active period of the system following said last-mentioned inactive period after said prime mover has reached its normal operating speed and for maintaining said compressor partially unloaded until the pressure in the low-pressure side of the system approaches the value normally prevailing therein during an active period, and means for controlling the pressure in the low-pressure side of the system to maintain the same at a substantially constant average value during said active periods, said last means comprising unloading means for fully loading the compressor at one pressure prevailing in the low-pressure side of the system and for partially unloading the compressor at lower pressures in the low-pressure side of the system.

2. In a refrigerating system having a high-pressure side including a refrigerant condenser and a low-pressure side including a refrigerant evaporator for cooling a media, the combination of a refrigerant compressor for withdrawing refrigerant from the low-pressure side of the system and compressing it into the high-pressure side of the system, a prime mover for driving the compressor, said refrigerating system having active and inactive periods and having a high pressure prevailing in the low-pressure side of

the system after an inactive period of such duration that the evaporator approaches ambient temperature, means for partially unloading the compressor during the first part of the active period of the system following said last-mentioned inactive period after said prime mover has reached its normal operating speed and for maintaining said compressor partially unloaded until the pressure in the low-pressure side of the system approaches the value normally prevailing therein during an active period, and means for controlling the temperature of said media to maintain the same at a substantially constant average value during active periods of the system, said last means comprising unloading means for fully loading the compressor at one temperature of said media, and for partially unloading the compressor at lower temperatures of said media.

3. In a refrigerating system having a high-pressure side including a refrigerant condenser and a low-pressure side including a refrigerant evaporator for cooling a media, the combination of a refrigerant compressor for withdrawing refrigerant from the low-pressure side of the system and compressing it into the high-pressure side of the system, a prime mover for driving the compressor, said refrigerating system having active and inactive periods and having a high pressure prevailing in the low-pressure side of the system after an inactive period of such duration that the evaporator approaches ambient temperature, means for partially unloading the compressor during the first part of the active period of the system following said last-mentioned inactive period after said prime mover has reached its normal operating speed and for maintaining said compressor partially unloaded until the pressure in the low-pressure side of the system approaches the value normally prevailing therein during an active period, said means also completely loading the compressor at one pressure prevailing in said low-pressure side of the system during an active period and partially unloading said compressor at lower pressures prevailing in said low-pressure side of the system, to maintain a substantially constant average pressure therein.

4. In a refrigerating system having a high-pressure side including a refrigerant condenser and a low-pressure side including a refrigerant evaporator for cooling a media, the combination of a refrigerant compressor for withdrawing refrigerant from the low-pressure side of the system and compressing it into the high-pressure side of the system, a prime mover for driving the compressor, said refrigerating system having active and inactive periods and having a high pressure prevailing in the low-pressure side of the system after an inactive period of such duration that the evaporator approaches ambient temperature, and means for partially unloading the compressor during the first part of the active period of the system following said last-mentioned inactive period after said prime mover has reached its normal operating speed and for maintaining said compressor partially unloaded until the pressure in the low-pressure side of the system approaches the value normally prevailing therein during an active period, said means also completely loading the compressor at one temperature of the media during an active period and partially unloading said compressor at lower temperatures of said media, to maintain a substantially constant average temperature therein.

5. In a refrigerating system having a high-pressure side including a refrigerant condenser

and a low-pressure side including a refrigerant evaporator for cooling a media, the combination of a refrigerant compressor for withdrawing refrigerant from the low-pressure side of the system and compressing it into the high-pressure side of the system, a prime mover for driving the compressor, said refrigerating system having active and inactive periods and having a high pressure prevailing in the low-pressure side of the system after an inactive period of such duration that the evaporator approaches ambient temperature, an unloading mechanism for said compressor, means for actuating said unloading mechanism to partially unload the compressor during the first part of an active period following said last-mentioned inactive period after said prime mover has reached its normal operating speed and for maintaining said compressor unloaded until the pressure in the low-pressure side of the system approaches the value normally prevailing therein during an active period and for then fully loading the compressor, and means for thereafter actuating said unloading mechanism to partially unload the compressor as the refrigerating load on said evaporator decreases.

6. In a refrigerating system having a high-pressure side including a refrigerant condenser and a low-pressure side including a refrigerant evaporator for cooling a media, the combination of a multi-cylinder refrigerant compressor for withdrawing refrigerant from said low-pressure side and compressing it into the high-pressure side, a motor for driving the compressor, said refrigerating system having active and inactive periods and having a high pressure in said low-pressure side after an inactive period of such duration that said evaporator approaches ambient temperature, and means adapted to unload at least one of said cylinders and to load at least one of said cylinders during the first part of the active period of the system following said inactive period after the motor has reached its operating speed and for maintaining at least said one cylinder unloaded until the pressure in the low-pressure side of the system approaches the value normally prevailing therein during an active cycle of said system.

7. In a refrigerating system having a high-pressure side including a refrigerant condenser and a low-pressure side including a refrigerant evaporator for cooling a media, the combination of a multi-cylinder refrigerant compressor for withdrawing refrigerant from said low-pressure side and compressing it into the high-pressure side, a motor for driving the compressor, said refrigerating system having active and inactive periods and having a high pressure in said low-pressure side after an inactive period of such duration that said evaporator approaches ambient temperature, an unloading mechanism for said compressor, means for actuating said unloading mechanism to unload at least one of said cylinders during the first part of an active period following said last-mentioned inactive period after the motor has reached its operating speed and for maintaining at least said one cylinder unloaded until the pressure in the low-pressure side of the system approaches the value normally prevailing therein during an active period and for then fully loading the compressor, and means for thereafter unloading at least one of said cylinders in response to a decrease in refrigerating load on said evaporator.

8. A control for a refrigerating system having

9
a low-pressure side and a high-pressure side including a multi-cylinder compressor and driving means for the compressor, said control comprising means for energizing said compressor driving means in response to a predetermined demand upon said refrigerating system, an unloader mechanism for unloading and loading one or more but not all the cylinders of said compressor, means controlling said unloader mechanism to load the associated cylinder or cylinders in response to increase in said demand to a second and

5 higher predetermined value and to unload the associated cylinder or cylinders upon decrease in said demand below said second predetermined value, and means responsive to increase in the pressure in the low-pressure side of the refrigerating system to a predetermined value above the normal pressure for controlling said unloader mechanism to unload the associated cylinder or cylinders independently of the action of said 10 means responsive to demand upon the system.

REGIS D. HEITCHUE.
